Fig. 6.

FIG. 1 is a side elevational view of a knife embodying my design.

FIG. 2 is a top plan view of the knife.

FIG. 3 is a transverse sectional view through the knife blade taken on the line 3—3, FIG. 1.

FIG. 4 is a transverse sectional view through the knife handle taken on the line 4—4, FIG. 1.

FIG. 5 is a transverse sectional view through the knife handle taken on the line 5—5, FIG. 1.

FIG. 6 is a transverse sectional view through the knife handle taken on the line 6—6, FIG. 1.

The design is intended for use on sets comprising knives, spoons, forks, and similar articles of flatware and the characteristic features of my design reside in the streamlined contours of the handle of the flatware.

This is a division of design application Ser. No. 25,238 filed Sept. 28, 1970, and now abandoned.

I claim:

The ornamental design for a knife or similar article of flatware, as shown and described.
